UNITED STATES PATENT OFFICE.

JAY E. TRAVER, OF NAUGATUCK, CONNECTICUT, ASSIGNOR TO THE GOOD-
YEAR'S METALLIC RUBBER SHOE COMPANY AND THE GOODYEAR'S
INDIA RUBBER GLOVE MANUFACTURING COMPANY, OF NAUGATUCK,
CONNECTICUT, CORPORATIONS OF CONNECTICUT.

FASTENER.

SPECIFICATION forming part of Letters Patent No. 707,369, dated August 19, 1902.

Application filed July 6, 1900. Serial No. 22,694. (No model.)

To all whom it may concern:

Be it known that I, JAY E. TRAVER, a citizen of the United States, and a resident of the town of Naugatuck, in the county of New Haven 5 and State of Connecticut, have invented new and useful Improvements in Fasteners, of which the following is a specification, reference being had to the accompanying drawings, forming part thereof.

10 My invention relates to fasteners adapted for securing together the parts of shoes, garments, belts, and other articles.

The objects of my invention are permanency of adjustment, the operations of fastening and unfastening not disturbing the adjustment, accuracy of adjustment, the adjustment being to any desired point, reliability of action, the fastener being non-slipping, although holding an unperforated flexible 20 tab without marring the tab, readiness and ease of manipulation, smooth finish and absence of protruding parts, the comfort of the wearer, simplicity and cheapness of construction, strength and durability, and other advantages, as will hereinafter appear.

The accompanying drawings illustrate an embodiment of my invention in the form in which I purpose applying it as a fastener for 25 overshoes.

Figure 1 is a front elevation of the upper portion of an overshoe having two fasteners embodying my invention thereon. Fig. 2 is an enlarged part horizontal section of the 30 same on the line 2 2, Fig. 1. Fig. 3 is an enlarged face elevation of the slide detached. Fig. 4 is an enlarged face elevation of the loop detached.

According to my invention the fastener 40 comprises two parts, one part consisting of a flexible strap or tongue of the garment, shoe, &c., which part I herein denominate a "tab," and an adjustable part or slide on the tab, and the other part constructed to receive the 45 tab with the adjustable part or slide thereon and to engage the same to hold the parts of the fastener together and to disengage the same to permit the separation of the two

parts of the fastener. According to my invention the engagement and disengagement 50 of the parts of the fastener does not disturb the relationship of the adjustable part or slide and the tab.

In the fastener embodying my invention shown in the accompanying drawings the 55 part upon the tab *a* consists of a slide *b*, having three cross-bars *g*, *e*, and *g*, and the other part of the fastener comprises the loop *c*, having a curved front cross-bar *h* and a rear fastening cross-bar *j*. The slide *b* slips over 60 and engages the tab *a*, which passes behind an outer cross-bar *g*, in front of the middle cross-bar *e*, and behind the other outer cross-bar *g* thereof, so that the outer cross-bars of the slide are in front of the tab. The slide 65 *b* is wider than the opening in the loop *c*, but may be inserted within the loop without detachment from or disturbance of its adjustment on the tab, and in the construction shown this is provided for by making the 70 opening in the loop *c* of sufficient length to permit the slide and tab to be entered obliquely therein, but with the slide nearly or substantially parallel to the loop. In the construction shown the slide *b* is caused to 75 enter at the rear of the opening and comes through and in front of the loop *c*, and after it has been thus brought in front of the loop the ordinary tension of the parts will bring it back against the face of the loop 80 and it will press against the face of the loop, and the parts of the fastener will be held together and cannot be disengaged under any 85 of the conditions of use. Disengagement of the parts can only be effected by moving the slide and tab in the opposite direction from that of the stress of the parts of the fastener, twisting the tab and slide to oblique position, and moving the slide and tab rearwardly out 90 through the loop, thus reversing the operation of inserting the tab and slide in the loop. The upper fastener in Fig. 1 is shown with the parts disengaged, while the lower fastener is shown with the parts engaged. The end of the tab *a* may be allowed to project, as shown, 95 or may not be brought in front of the loop

or may be brought out in front of the loop and then tucked in behind the loop and flap *d* of the shoe. According to my invention the inner cross-bar of the slide is provided with one or more projections, which press upon and to some extent into the material of the flexible tab and insure a tight grip of the slide upon the tab, so as to prevent slipping of the slide upon the tab. In the construction shown the inner or middle cross-bar *e* of the slide *b* is provided with two projections *f f*, one on each side of the cross-bar and located medially thereon. As the tab *a* is flexed or curved in passing in front of the middle cross-bar *e* from behind the outer cross-bars *g g* on each side of the middle bar, the material of the tab will be very tightly pressed against the projections *f f*, and a very tight grip will result from this construction. This gripping action is also assisted by the curved shape of the outer cross-bars *g g*, which grip the tab tightly in proximity to its edges. When the parts of the fastener are engaged, the cross-bar *h* of the loop *c* is between the tab and slide, as clearly shown in Fig. 2, the cross-bar *h* of the loop being just in rear of the left-hand outer cross-bar *g* of the slide. This tends to press the tab more tightly against the left-hand projection *f* of the middle cross-bar of the slide, and any tension applied to the tab would still further increase this pressure, and thus the grip of the slide on the tab would be tightened as the tension on the tab increased, and with my improved construction the slide will be so tightly held upon the tab that it cannot slip under any of the conditions of use. Nevertheless the slide may be readily adjusted to desired position, as it is only necessary to loosen the loop in the tab to bring the parts in such position that the slide may be moved to desired position on the tab, and it will be observed that this adjustment may be as fine and accurate as desired, as the slide may be held at any desired point. It will be noted that the engagement and disengagement of the fastener does not disturb this adjustment of the slide upon the tab, and therefore the adjustment having been once made to suit the conditions of use may be permanently retained or retained until the conditions of use are changed.

In the construction shown in the drawings the two tabs *a a* (shown in Fig. 1) are secured to and project from the flap *i* of the shoe and the loops *c c* are secured to and project from the flap *d* of the shoe. I prefer to flatten the inner fastening-bar *j* of the loop *c*, as shown, so that a comparatively flat finish will be obtained where this fastening-bar enters between the layers of the material of the overshoe, and this loop may be formed from wire without soldering the ends, as shown, the fas-

tening-bar *j* being composed of two parts meeting or nearly meeting at or about the middle of the bar.

65

It will be noted that the construction of the fastener is exceedingly simple and inexpensive and that there are no parts liable to derangement and also that the parts of the fastener have a smooth finish. The employment of a tab of cloth or other soft material is desirable, as such a tab is soft and comfortable to the wearer and much to be preferred to any metallic strap or tab such as employed in many other forms of fastener.

75

It is evident that various modifications may be made in the construction above particularly described within the purview of my invention and that in the application of my fastener to various uses modifications of construction may be desirable.

80

What I claim, and desire to secure by Letters Patent, is—

1. A fastener comprising two parts, one part consisting of a tab with an adjustable slide thereon and the other part consisting of a loop provided with an opening therein, the dimensions of the slide and opening being so related that in one position thereof, with the slide and loop substantially parallel, the slide may be passed through the opening in the loop, and in the normal position thereof, with the slide and loop engaged, a portion of the margin of the slide will bear against the loop about the opening, the slide having a cross-bar with one or more projections thereon whereby it grips the tab and retains the position to which it is adjusted upon the tab and is not disturbed therefrom by engagement or disengagement of the slide and loop, substantially as set forth.

95

2. The combination with a tab and a slide thereon, the slide having a cross-bar with one or more projections thereon, of a loop constructed to engage between the tab and slide and having an opening therein narrower than the slide and longer than the greatest dimension thereof, substantially as set forth.

105

3. A fastener comprising two parts, one part consisting of a tab and a slide, such slide *b* having a middle cross-bar *e* with projections *f* thereon and outer curved cross-bars *g g*, and the other part consisting of a loop having an opening narrower than the slide and longer than the greatest dimension of the slide and wider than the tab, substantially as set forth.

110

This specification signed this 22d day of June, 1900.
